UNITED STATES PATENT OFFICE.

ALFRED YATES, OF SOMERVILLE, MASSACHUSETTS.

DOWNDRAFT CONTINUOUS BRICK-KILN.

SPECIFICATION forming part of Letters Patent No. 719,974, dated February 3, 1903.

Application filed April 22, 1901. Serial No. 56,813. (No model.)

To all whom it may concern:

Be it known that I, ALFRED YATES, a citizen of the United States of America, and a resident of Somerville, in the county of Middlesex and State of Massachusetts, have invented certain new and useful Improvements in Downdraft Continuous Brick-Kilns, of which the following is a specification.

My invention relates to brick-kilns; and it refers particularly to improvements not existing in my previous patent, No. 264,118, of date September 12, 1882.

The improved features of my present invention consist in the arrangement of the flues within and beneath the kiln-floor, the employment of dampers to regulate the currents of air and heat, the radial partition-walls provided with arched openings at the bases thereof, the construction of a permanent floor over a labyrinth of air-passages, the arrangement of the several diverse courses of bricks upon the floor of the chambers, the temporary flash-walls surmounting the fire-walls, the combination of several connected accessible chambers adapted to the diverse operations of brick-making simultaneously under one dome, and in other fundamental changes in construction and acquisition of new features hereinafter enumerated, the above aggregation comprising a vertical downdraft continuous kiln.

I attain the objects of my invention by the oblong and circular construction illustrated in the drawings hereunto annexed, in which—

Figure 1 is a ground plan exhibiting the flues within and beneath the floor of the kiln. Fig. 2 is a plan denoting the several consecutive workings and also illustrating the manner of laying down the check and draft courses of brick preliminary to the piling of the stacks preparatory to the burning. Fig. 3 exhibits in longitudinal transverse section the construction of the kiln-walls, arrangement of the flues and chambers, and the disposition of the furnaces on dashed line 3 3 of Fig. 4, with the floor of two end chambers in horizontal section to exhibit the system of parallel arches and passages leading therefrom, with the auxiliary flues and passages connecting with the main flues leading to the chimneys. Fig. 4 is a vertical longitudinal central section exhibiting the arches and air-spaces in the walls and

floor with the flues and their connection with the chimneys on dashed line 4 4 of Fig. 3. Fig. 5 is a plan of the flues and passages of the circular kiln, and Fig. 6 a transverse section of the kiln constructed above said flues and passages.

Corresponding letters of reference designate like parts throughout the drawings, referring to which—

A represents the central yard, accessible by openings through the inner wall of one or more of the chambers when empty, as in Fig. 3, wherein are situated a series of furnaces B in the inner wall C of the kiln, adjacent and parallel to which arises the flash-wall D. The intervening space E permits the heated air from the furnaces B to pass up and over the said flash-wall D, whence it circulates downwardly through the stacked goods. The arrangement of the outer wall C', the series of furnaces B', the flash-wall D', and the intervening spaces E' E' are identical in their construction and operation, the heat radiating in a similar manner. After ramifying through the stacked wares the heat passes through the check and draft rows, Fig. 2, underlying all the wares downwardly, and through the skittle-bricks G, filling the smaller radial open flues H' H' H' in the kiln-floor, Fig. 3. Thence the heat radiates through the arched flues L' into the transverse passages L', passing into the inner and outer auxiliary flues L' L', finally reaching the main flues I I' lowest situated underground parallel with the main walls of the kiln, the products of combustion escaping through the inside and outside chimneys J J', Fig. 3, the former, J, connecting with the inner main flue I, while the latter, J', communicates with the outer main flue I'. The main walls are efficiently strengthened by ordinary vertical channel-irons and tie-rods, properly connected, as illustrated, and furnished with entrances to each chamber, which are sealed up temporarily while the goods are being burned. The partition-walls are shown at C' separating the individual kilns or chambers K, wherein the various processes of brick-making are simultaneously developed and which will subsequently be described. Arches L, Fig. 4, are formed in the base of each partition-wall C' near the floor to per-

mit a free circulation throughout the series of chambers K, the volume of air thereto being controlled by the depending covers M, supported by and sliding upon ledges N, projecting from the partition-walls C². Said covers M are manipulated by hand-rods O, thrust through openings in the inner or outer walls C C' or through both, as desired.

Upon the permanent flash-walls D D', Fig. 4, are laid the temporary flash-walls D², whose purpose is to confine the heat within the stack of burning wares while following the shrinkage thereof occasioned by the heat.

The floors of the several chambers or kilns K are permanently laid down over a series of parallel arched flues L', Fig. 3, to insure additional radiating-surface under each chamber, thus utilizing the surplus heated air from the bottoms of the kilns and to assist in drawing the heat away from the lower courses of burning wares, which then produces brick of a uniform hardness with those in remote parts of the stacks. Said arches collectively communicate with radial passages L² near the base of each of the partition-walls C² and also with the radial passages L⁶ L⁷ and the open flues H' H² H³. Said passages also connect with the subterranean auxiliary passages L⁸ L⁴, following the contour of the inner and outer flues I I', and thus permit a distribution of this heated air through the arches L' into passages L² L⁶ L⁷, thence to auxiliary flues L³ L⁴, controlled by dampers P' P' and the dampers P P, which direct the air-currents into the air-spaces E' and into the chambers, their separate manipulation being hereinafter explained.

The above description applies to the construction shown in Fig. 3. The draft in the round kiln, Fig. 6, being controlled by dampers similarly located, the heat from the inner and outer series of furnaces, Fig. 6, filling the several flues and passages entering the flues I², Fig. 5, thence converging to the central chimney J⁴ and passing off to the atmosphere.

Underlying the wares to be burned are the skittle, draft, check, and bond courses, Fig. 2, comprising brick, preferably, permanently laid down upon their edges to form a foundation for the wares to be burned and also to insure a uniform circulation and distribution of hot air for drying and burning and cold air for cooling the goods. The skittle-brick are diagonally laid, one above another, as at G, filling the depth and length of the flues H' H² H³ to the height of the draft-rows F, which are next laid upon the floor of each chamber in the manner illustrated in Fig. 2, comprising, preferably, two courses of superimposed bricks the single bond-rows are at F' laid at right angles with the draft-rows, and finally the single checking-rows F² laid, as illustrated, and in the direction of the double draft-rows, the above features being collectively summarized as "check" and "draft" and which complete the foundation.

In the utilization of these kilns the following processes are concurrent: (see Fig. 2,) first, setting green brick; second, water-smoking and drying; third, clearing; fourth, burning brick; fifth, cooling off same; sixth, removing the wares, the several workings being well known to those skilled in this art and need but brief mention in the subsequent disclosure. The operation of water-smoking and drying, assuming several chambers filled with green brick, proceeds as follows: The fuel is ignited in the inner and outer furnaces connected with the chamber to be dried, the heat entering through fire-arches B B' in base of main walls C C' and ascending the air-spaces E E', passing over the flash and temporary flash walls D D', filling the chambers K K, thence descending through the mass of green bricks or clay goods stacked in the several chambers distributes through the check and draft rows F F' F² with a uniform radiation, passing into the open flues H' H² H³, piled with loose brick, which may be temporarily or permanently laid, thence into the arched flues L', through radial passages L² L⁶ L⁷ into auxiliary flues L³ L⁴ and into inner and outer main flues I I', which lead to and connect with the chimneys J J'. The dampers meanwhile are regulated to increase the draft in the desired direction or reduce it proportionately, as follows: For convenience the green wares may be divided into three or more vertical sections of bulk in each chamber and dried in such order, commencing with chamber No. 1, Fig. 3, the heat traveling to the right in flues I I' L³ L⁴. The dampers P P in the flues L⁵ L⁵ connecting with the inner and outer auxiliary flues are opened, permitting the heat to pass into the air-spaces E², while the dampers P' P' are closed to prevent the heat traveling rearwardly along the auxiliary flues L³ L⁴. The heat now radiates over the flash-wall, descending through the mass of goods into the first flue H', thence into the arched flues L', returning under the floor and emptying into the first radial passage L². The dampers P² P² are now opened, heat passing forward or to the right along the auxiliary flues L³ L⁴ until the first section is water-smoked and dried. They are then closed and the dampers P³ P³ are opened, the heat traveling, as before, through flues H² and passage L⁶ until the next section is water-smoked and dried. Said dampers are then closed and dampers P⁴ P⁴ are opened, heat entering through flue H³ and passage L⁷ into flues L³ L⁴ until the last section is water-smoked and dried. (See arrows, Fig. 4.) Following the evaporation of the exudation from the green clay the dampers P' P' are closed, with dampers P P open and covers M M (previously closed) opened, thus regulated to draw off the smoke and clarify the goods preparatory to burning. This stage is known as "clearing." At intervals are placed the short flues I⁴ I⁴, connecting the auxiliary flues L³ L⁴ with the main

flues I I'. Dampers P⁵ are provided therein whose office is to check the heat from passing into the latter flues and escaping through the chimneys during the operation of drying.

5 The main flues I I' are additionally dampered contiguous to the chimneys, as at P⁶ P⁶, and also in the exits I⁵ I⁵, entering said chimneys, by dampers P⁷ P⁷. These may be considered the principal dampers controlling the system.

10 The heat is now augmented, and the firing proceeds until the bricks are sufficiently burned. In this way the system is conducted in a consecutive manner from one chamber to the other, the waste heat drying the green

15 goods in advance, the dampers, similarly situated in each chamber, being regulated as in the previous example, the water-smoking and drying preceding the clearing and burning. After the latter operation is completed the

20 several covers and dampers are regulated to exclude the heat from the goods that have been burned and from such chambers and the ensuing stage of "cooling-off" is reached. After a sufficient time has elapsed "removing the brick" completes the operation.

25 S succinctly, this illustrates the working capacity of my improved continuous vertical down-draft, oblong, and round kiln.

Having ascertained these improvements

30 through the preferred details of construction illustrated, they are subject to modifications which would not depart from the spirit of my invention and are intended to be included in the claims.

35 I claim—

1. A brick-kiln having a series of chimneys without the outer wall, the outside subterranean main flues coacting with said chimneys, the series of chimneys situated within the 40 inner wall, the inside subterranean main flue arranged to coact with said inside chimneys, the exits to the chimneys from said outside and inside subterranean flues and the dampers P⁶ in said flues and dampers P⁷ in said 45 exits to govern the draft substantially in the manner and for the purpose herein specified.

2. In a vertical downdraft-kiln for burning brick the combination with the inner and outer main flues I, I', the flues L', the passages 50 L², the auxiliary flues L³, L⁴, and the open flues H', H², H³, of the short flues I⁴ connecting said auxiliary flues with the main flues, and the dampers P⁵ adapted to check the heat, when desired, from passing into said auxiliary and main flues and escaping through the 55 chimneys when drying out the wares substantially in the manner specified.

3. In a downdraft brick-kiln the combination with the several chambers, the open flues 60 leading therefrom, the arched flues beneath the chambers, the passages leading from the arched flues, the auxiliary flues connected with each end of said passages, the short flues I⁴, and the main inner and outer flues, of the 65 flues L⁵, L⁵, connecting the auxiliary flues with the air-spaces E² in the partition-walls C² and the dampers P permitting heat to pass

into said air-spaces, when the dampers P' in said auxiliary flues are closed substantially as and for the purpose set forth. 70

4. In a kiln adapted to setting, drying, clearing and burning brick simultaneously, the combination with the subterranean arched flues L', the radial passages L², the auxiliary distributing-passages L³, L⁴, and the open 75 flues H', H², H³, of the underground flue I, communicating with the chimneys in the yard, and the flue I', similarly situated, connecting with the chimneys outside the kiln-walls, substantially in the manner and for the 80 purpose set forth.

5. The combination with the arched subterranean flues, the radial passages leading therefrom, the auxiliary flues communicating with said passages, the outer and inner main 85 flues and the dampers P⁶ P⁷ governing the flue circulation, of the series of chambers collectively forming a continuous kiln, provided with open flues establishing connection with the arched subterranean flues and coacting 90 circulating-passages, and having means adjacent to the floors of said chambers to allow unimpeded air circulation throughout the kiln and the means integral with the chamber-walls C² to retard and accelerate said air 95 circulation substantially as specified.

6. In a brick-kiln, the outside chimneys arranged to coact with the outer and subterranean flue, the inside chimneys arranged to coact with the inside subterranean flue, the open flues H', H², H³, adapted to draw the 100 heat from the burning stacks, the series of parallel arches beneath the floors of the chambers, the transverse passages communicating therewith, the inside and outside auxiliary 105 flues arranged to receive and distribute the heat, the main inner and outer flues communicating with their respective chimneys, and the dampers P², P³, P⁴, at each end of said passages L², L⁶, L⁷, to govern the draft 110 and conserve the heat within the kiln substantially in the manner specified.

7. The hereinbefore described arrangement of the inside and outside flues connecting with the inside and outside chimneys, the 115 system of flues and passages distributing air and heat and the dampers therein governing such distribution, in combination therewith the series of communicating chambers having flues for the vertical downward transmission 120 of air to said system of flues and passages and means provided on the floor of each chamber arranged to secure uniform circulation and form a foundation substantially as described and illustrated for the body of 125 green brick preparatory to being cured and burned.

Signed by me at Boston, Massachusetts, this 19th day of March, A. D. 1901.

ALFRED YATES.
